(57) **CLAIM**

The ornamental design for a camera, as shown and described.

DESCRIPTION

FIG. 1 is a front, top, left perspective view of a camera showing my new design;

FIG. 2 is a back, bottom, right perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a back perspective view thereof shown in a state of use; and,

FIG. 10 is an enlarged portion view thereof taken from encircled portion labeled “10,” in FIG. 2.

The dashed-dot lines form the boundary of the enlarged portion view of FIG. 10 in the drawing view of FIGS. 2 and 10 and form no part of the claimed design. The even dashed broken lines shown in the drawings are included for the purpose of illustrating portions of the camera that form no part of the claimed design.
